(57) CLAIM

The ornamental design for a football, as shown and described.

DESCRIPTION

FIG. 1 is a front perspective view of a football showing my new design;

FIG. 2 is a top view thereof;

FIG. 3 is a bottom view thereof;

FIG. 4 is a right side view thereof, with the unseen left side view being a mirror image thereof; and,

FIG. 5 is a front view thereof, with the rear view being a mirror image thereof.

The grayscale shading represents a contrast in either grayscale tone or color consonant with the visual appearance shown in the drawings.

The broken lines are included for the purpose of illustrating a portion of the football that forms no part of the claimed design.
